FOOT ALIGNING ROD FOR X-RAYING PATIENTS

Louis E. Kroll, Cass County, Mich.
(1515 S. Nappanee St., Elkhart, Ind.)

Filed May 3, 1963, Ser. No. 74,737

Term of patent 7 years

(Cl. D83—1)

FIG. 1

6 →

FIG. 5

FIG. 4

FIG. 6

FIG. 7

FIGURE 1 is a perspective view of a foot aligning rod for X-raying patients embodying the present novel design;

FIGURE 2 is a side elevational view of the foot aligning rod shown in FIGURE 1;

FIGURE 3 is an elevational view of the underside of the foot aligning rod shown in FIGURES 1 and 2;

FIGURE 4 is a rear elevational view of the present foot aligning rod;

FIGURE 5 is a horizontal cross sectional view of the present rod, the section being taken on line 5—5 of FIGURE 2;

FIGURE 6 is a partial vertical cross sectional view taken on line 6—6 of FIGURE 5;

FIGURE 7 is a partial vertical cross sectional view taken on line 7—7 of FIGURE 3; and

FIGURE 8 is a cross sectional view taken on line 8—8 of FIGURE 3.

I claim:

The ornamental design for a foot aligning rod for X-raying patients, substantially as shown.
